UNITED STATES PATENT OFFICE.

PETER L. MAHER, OF CLEVELAND, OHIO, ASSIGNOR TO THE DAMASCUS BRAKE BEAM COMPANY, OF CLEVELAND, OHIO, A CORPORATION OF OHIO.

REVERSIBLE FULCRUM FOR TRUSSSED BRAKE BEAMS.

Application filed October 20, 1919. Serial No. 331,774.

To all whom it may concern:

Be it known that I, PETER L. MAHER, a citizen of the United States, residing at Cleveland, in the county of Cuyahoga and State of Ohio, have invented certain new and useful Improvements in Reversible Fulcrums for Trussed Brake Beams, of which the following is a specification.

The present invention relates to a fulcrum for trussed brake beams, which has its slotted portion that receives the brake lever movable about its longitudinal axis in order to permit the brake lever to assume different positions. It has long been proposed to produce brake beam fulcrums of this general type by the process of casting the parts thereof, the castings being subsequently malleablized to reduce danger of fracture. But fulcrums so constructed have proven generally unsatisfactory.

The object of the present invention is to devise a fulcrum of forged steel which shall embody in its construction the feature of angular adjustability by rotation of that portion of the fulcrum which carries the slot to receive the brake lever; and to accomplish this while leaving the slot member of the construction as the only connection between portions of the fulcrum which, respectively, connect with the compression member and the tension member of the brake beam.

The invention resides in the form and inherent structural characteristics of the three members of the fulcrum, as hereinafter described and particularly pointed out in the claims, reference being had to the accompanying drawings, in which,

Figures 1 and 2 are two views of the assembled fulcrum with associated portions of the compression and tension members of the brake beam.

Figure 3 represents, by segregated views, side elevations of the three members which go to make up the fulcrum, together with face views of those ends of these several members which come together in their assembly.

Figure 3^a is a modification of the connection between the body member and the head; and

Figure 4 is a detail view showing a modified construction of the foot of the fulcrum; and

Figures 5 and 6 show another modification thereof.

1 represents the slot member of the fulcrum, the general form of which is that of an elongated rectangular frame with straight side walls 1^a spaced apart to leave the lever slot 2 between them and with holes 3 to receive the pintle of the brake lever, and with squared ends 4, 4^a integral with and yoking the sides together, providing square abutments upon their faces for the coacting members of the fulcrum. The slot member 1 is forged from rolled steel bar in a manner to produce an elongated rectangular link. Its sides 1^a being perfectly straight and perpendicular to its ends are adapted to transmit the large loads which these structures are designed to bear without danger of deflection, notwithstanding the fact that the sides of the rectangular frame-like link are of flat rolled structural steel and without lateral braces, ribs, or other stiffening expedients.

5 represents the head of the strut or fulcrum which is provided with the usual saddle 6 to receive the tension member 7. This saddle is shown shaped to receive a tension member of round section, but it may be shaped to receive any section of tension member desired. In accordance with the present invention, the head 5 is constructed with a swivel stud 8 fitted accurately to the turning bearing 9 in the outer end of the slot member 1 and upset to provide a flange 10 that prevents its withdrawal from said bearing. Head 5 is thus adapted to permit the slot member to turn about the longitudinal axis of the fulcrum and present the slot in different angular relations to the horizontal plane of the brake beam. It is constructed of steel forging, and its base 5^a is of such form that it provides a substantial bridge across the end of the slot member and transmits the load of the tension member 7, developed under the thrust of the fulcrum, longitudinally upon the side walls 1^a of the slot member 1 at all times, notwithstanding its angular displacement relatively thereto. The construction and assembly of the head 5 with the slot member 1 involves a relatively short dimension between the flange 10 and the saddle 6, and thereby affords an ample length of slot 2, which is an important feature in the proper operation of the brake lever.

11 represents the foot-member of the strut or fulcrum, which, aside from embodying

the characteristics below described, is given such form as will adapt it to the particular section of compression member employed in the brake beam. For instance, it is given the 5 so-called arrowhead form when the fulcrum is to be connected through the well known clip 12 and bolt 12^a to the angle form of compression member 13, as shown in Figures 1 to 3; or it may have its anchoring 10 end constructed with the standing form 11^a when it is to be riveted to the web of a channel section 13^a (Figures 4); or it may be in the form of an embodied clip 11^b drawn 15 tightly upon the compression member by clip-bolt 12^a (Figures 5 and 6) when it is to embrace a channel section 13^a or an I-section; or, as stated, it may be given any other form desired. The foot-member 11, 11^a, or 11^b is constructed of rolled steel bar, 20 forged to provide straight sides 14 extending in the line of pull imposed upon the compression member to the transverse connecting bar or yoke 15 bent sharply across the ends thereof, and with a perforation 16 in the cross bar thus formed to receive the 25 swivel stud 17 of the slot member 1. The swivel stud 17 is provided with a head or flange 18 within the cross bar 15 of sufficient dimension to transmit the pull, through the foot-member 11 or 11^a, to the 30 compression member 13. At the same time swivel 17 permits angular displacement of the slot member 1 about its longitudinal axis relatively to the foot-member 11 or 11^a. 35 When held by the bolt 12^a from the clip 12, as in Figure 1, or by the rivets 12^b from another form of compression member, as suggested in Figure 4, the foot-member 11 or 11^a is anchored to the compression member 40 at points in the line of its straight sides 14 so that the strains are all distributed in lines that will avoid distortion of the foot member.

The swivel studs 8 and 17, and especially 45 the latter, having their flanges forged upon the ends thereof, are preferably pressed in the direction of the axis of the fulcrum so as to bring their flanges, as well as the opposing faces of the members which carry them, 50 into firm bearing upon the yokes or cross bars 4 and 4^a, and thereby avoid all lost motion or vibration between these parts. The connection between the slot member 1 and the foot-member 11 or 11^a, like that at the 55 outer end of the fulcrum, by reason of its form and the material of which the parts are constructed requires but a relatively short longitudinal dimension for the necessary strength and stability of the parts, and thus 60 leaves ample length of lever slot.

It is to be noted that as the arrowhead form fits in the angle 13, or as the out-turned extensions of the foot-member 11^a are riveted to the compression member, the side 65 walls 14 of the foot member are fixed against

lateral displacement, and the connection through which pull is imposed upon the compression member by the rivets of Figure 4 and by the bolt 12^a of Figure 1 is in alignment with said side walls 14. Moreover, in Figure 1, the bolt 12^a assists in holding the side walls against lateral displacement.

Preferably, there will be associated with one of the swivel joints, for instance, the joint at the head of the fulcrum, means for 75 limiting angular movement of the body member relatively to the head and foot members. This may be either the lugs 19 on the front end of the body member entering segmental recesses 20 in the rear face 80 of the head block 5, as shown in Figure 3, or lugs 19^a on the latter entering segmental recesses 20^a in the former, as shown in Figure 3^a.

I claim:

1. An angularly adjustable brake beam fulcrum, comprising a slotted body member and head and foot members having swivel connections therewith, said body member being constructed of rolled structural steel fashioned to provide straight parallel side bars and end walls extending perpendicularly thereto and integrally uniting the same, said foot member being also constructed of rolled structural steel fashioned to provide a portion for coacting with the compression member and a transverse end wall swivelly connected to the end wall of the body member, the compression being transmitted from said foot member longitudinally 95 upon said side bars substantially in direct alignment therewith at all angular adjustments of said foot member.

2. An angularly adjustable slotted brake beam fulcrum, comprising a body member and end members having swivel connections therewith; said body member being constructed of rolled structural steel fashioned to provide straight parallel side bars of parallelogram section, and end walls extending 110 at right angles thereto, integrally uniting the same and providing flat inner and outer faces perpendicular to said bars; an end member being in flat bearing upon an outer perpendicular face of an end wall; and the 115 swivel thereof being carried by said end member having a flat head firmly pressed against the inner flat face of said end wall.

3. An angularly adjustable slotted brake beam fulcrum, comprising a body member 120 and end members having swivel connections therewith, said body member being constructed of rolled structural steel fashioned to provide straight parallel side bars and end walls extending at right angles thereto, integrally 125 uniting the same and providing flat outer bearing faces perpendicular to said bars, an end member having a surface in flat bearing engagement with one of said flat outer bearing faces and swivelly connected with the 130

adjacent end wall, the compressive force exerted through said end member being transmitted upon said side bars substantially in direct alinement therewith at all angular adjustments of said end member.

4. An angularly adjustable slotted brake beam fulcrum, comprising a body member and head and foot members having swivel connections therewith; said body member being constructed of rolled structural steel of rectangular section fashioned to provide straight parallel side bars, and end walls extending perpendicularly thereto and integrally uniting the same; and said foot member being also constructed of rolled structural steel fashioned to provide straight side walls adapted to aline with the side bars of the body portion and with a transverse end wall integrally uniting the same and united 20 with an end wall of the body member through its swivel connection.

5. An angularly adjustable slotted brake beam fulcrum, comprising a body member and head and foot members having swivel connections therewith; said body member being constructed of rolled structural steel of rectangular section fashioned to provide straight parallel side bars, and end walls extending perpendicularly thereto and integrally uniting the same; said foot member being also constructed of rolled structural steel fashioned to provide straight side walls adapted to aline with the side bars of the body portion and with a transverse end wall integrally uniting the same and united with 35 an end wall of the body member through its

swivel connection; and said foot member having means for tying together against lateral spreading its said side walls.

6. In an angularly adjustable fulcrum for 40 brake beams, a forged metal slot member having substantially straight sides with a connecting yoke, and a foot member constructed with substantially straight sides extending in the direction of transmission of 45 pull from the compression member, and connected by a cross bar having swivel connection with the link member; said foot member having means sustaining its side walls against lateral displacement; said last-named means comprising the bearings 50 through which the foot member meets the compression member.

7. In an angularly adjustable fulcrum for 55 brake beams, a forged metal slot member having substantially straight sides with a connecting yoke, and a foot member constructed with substantially straight sides extending in the direction of transmission of 60 pull from the compression member and connected by a cross bar having swivel connection with the link member; said foot member having means sustaining its side walls against lateral displacement; said last-named means comprising the bearings 65 through which the foot member meets the compression member; and a transverse bolt tying the side walls of the foot member together.

Signed at Cleveland, Ohio, this 14th day 70 of October, 1919.

PETER L. MAHER.
